D5379

EX

OR D 11,126

No. 11,126

MARCH 20, 1879

UNITED STATES PATENT OFFICE.

CORNELIUS JACKSON, OF PHILADELPHIA, PENNSYLVANIA, ASSIGNOR TO
THOMAS DOLAN AND R. WILLIAMS, JR., OF SAME PLACE.

DESIGN FOR KNITTED FABRIC.

Specification forming part of Design No. **11,126**, dated March 25, 1879; application filed December 7, 1878.
[Term of patent 3½ years.]

To all whom it may concern:

Be it known that I, CORNELIUS JACKSON, of Philadelphia, Pennsylvania, have invented a new and original Design for Knitted Fabric, of which the following is a specification:

My design is shown in the accompanying photographic illustration.

The design comprises alternating portions or stripes *a* and *b*, the portion *a* being plain, and composed of loops knitted comparatively closely, the portion *b* being composed of loosely-knitted loops, forming a groundwork, which is crossed at intervals by oblong bars *d*, the latter being puffed or raised, so as to contrast strongly with the groundwork, and being curved or waved, as shown.

My present design differs from that for which Letters Patent No. 10,979 were granted to me on the 7th day of January, 1879, not only in

having these stripes curved or waved instead of straight, but also in the character of the open groundwork on which the stripes are arranged.

Irrespective of the colors employed, I claim—

The design for a knitted fabric, said design comprising the plain and compactly-knitted portion *a* and the loosely-knitted portion *b*, crossed by curved or waved bars *d*, of a puffed or raised character, all substantially as described and shown.

In testimony whereof I have signed my name to this specification in the presence of two subscribing witnesses.

CORNELIUS JACKSON.

Witnesses:

ALEX. PATTERSON,
HARRY SMITH.
